ABSTRACT OF THE DISCLOSURE

A rotary switch is formed from a plurality of integral members, each of which has a ring portion electrically interconnecting a plurality of electrically conductive segments extending therefrom. Nonconductive material is molded between the conductive members so that the segments are spaced apart in electrically isolated relationship, yet form a substantially continuous common outer surface of conductive material. The molded nonconductive material is recessed from the common outer surface of the segments, and may cover the inwardly facing surface of the ring portion of one or more of the members.

This is a division of application Ser. No. 319,222, filed Oct. 28, 1963 now Pat. No. 3,411,201, entitled "Improved Rotary Switch Construction and Method For Manufacturing Same."

The present invention relates to electrical switches and more particularly, but not by way of limitation, relates to an improved rotary switch construction particularly adapted for use in the ignition system of internal combustion engines and to a method for manufacturing the switch.

It has been long recognized in the art that a rotary switch possesses many unique qualities of operation which are far superior to various types of switches employing opening and closing contacts. This is particularly true in internal combustion engine ignition systems wherein so-called points are used to interrupt an electrical circuit in timed sequence with operation of the engine in order to cause a spark and ignite the fuel in the engine. The basic approach taken by prior workers in the art was to provide a rotating switch member having alternate conductive and nonconductive segments and a brush riding against the rotating switch. However, the prior art workers all utilized alternate plastic and metal segments and were totally unsuccessful. The present inventor discovered that all of the segments which contacted the brush must be electrically conductive, and accordingly described such an ignition system and rotary switch in U.S. Pat. No. 3,087,000. However, before this type of switch could be made readily available to the public, not only for automobile ignition systems but for many other rotary switch applications, it was necessary to find a better means for mass-producing the switches on a more economical basis. Therefore, the present invention is particularly related to an improved rotary switch of the type disclosed in the above-referenced patent, and to a method for economically fabricating the rotary switch on a mass production basis. However, it is to be understood that the present invention, in its broader aspects, is not restricted to ignition systems for internal combustion engines.

The present invention contemplates a rotary switch member comprised of a plurality of electrically-conductive members, each having a plurality of segments with cylindrically-shaped outer surfaces. The segments of the various conductive members are spaced one from the other and, in combination, form a common, cylindrical

2

surface. The conductive members are interconnected and held in spaced, electrically-isolated positions by an electrically non-conductive member which will usually comprise a suitable plastic material.

The method of the present invention provides a means for fabricating the novel rotary switch comprising the steps of forming at least two integral members of electrically-conductive material each having one or more segments which are disposable in predetermined relationship to form a common cylinder or other suitable surface, orienting the members in spaced relationship, and molding a non-conductive material between the members to hold the members in spaced, electrically-isolated relationship.

Therefore, it is an important object of the present invention to provide an improved rotary switch construction which can be mass-produced on an economical basis.

Another object of the present invention is to provide a method for mass-producing a rotary electrical switch on an economical basis.

Still another object of the invention is to provide an improved rotary switch for replacing the breaker points of an automobile ignition system.

Another object of the present invention is to provide a rotary switch of the type described which may be quickly and easily installed in the ignition system of any one of the engines of the four major automobile manufacturers.

Yet another object of the invention is to provide a rotary switch of the type described having greater strength, particularly against centrifugal disintegration so that it can be operated at high speeds.

Many additional objects and advantages will be evident to those skilled in the art from the following detailed description and drawings, wherein:

FIG. 1 is a top view of a rotary switch constructed in accordance with the present invention;

FIG. 2 is a side view of the rotary switch construction of FIG. 1;

FIG. 3 is a sectional view taken on lines 3—3 of FIG. 1;

FIG. 4 is a sectional view taken on lines 4—4 of FIG. 1; and,

FIGS. 5a and 5b are perspective views of two component parts of the rotary switch of FIG. 1.

As previously mentioned, the present invention is related to the type of ignition system disclosed in my prior U.S. Pat. No. 3,087,000, and accordingly, the embodiment which will presently be described is particularly adapted for use in connection with a standard distributor for an eight-cylinder internal combustion engine of the type used in automobiles as described in my patent. In this type of ignition system, a timing shaft 5 (shown in dotted outline) is driven in synchronism with the engine and is provided with a polygon-shaped cam 6 (shown in dotted outline) having a number of sides corresponding to the number of cylinders of the engine. For example, an eight-cylinder engine would have an octagon-shaped cam as illustrated, while a six-cylinder engine would have a hexagon-shaped cam. The cam 6 normally actuates a set of mechanical breaker points which opens a circuit including a capacitor and the primary coil of a transformer and thereby induces a high voltage in the secondary winding of the coil which is applied to the appropriate spark plug by a distributor arm which is also connected to and rotates with the timing shaft.

A rotary switch constructed in accordance with the present invention is placed around the polygon-shaped cam 6 and one set of alternate segments of the switch are electrically connected to the cam, while the other alternate set of segments are electrically insulated from the cam as will presently be described. A brush 8 (shown in dotted outline) rides on the rotary switch. When the brush is in contact with the electrically-conductive segment, the circuit (not illustrated) including the primary

transformer winding is completed and when the brush is in contact with the insulated segments, the circuit is broken to induce an impulse in the secondary winding which is applied to the appropriate spark plug.

The rotary switch member 10 is comprised of a first electrically-conductive member, indicated generally by the reference numeral 12 (see FIG. 5a), and a second electrically-conductive member, indicated generally by the reference numeral 14 (see FIG. 5b). The member 12 is comprised of a ring portion 16 and a plurality of segment portions 18 each of which is connected to the ring portion 16 by a spacer portion 20. Each of the segments 18 has a cylindrical outer surface 18a. The outer surfaces of the several segments have a common radius of curvature and consequently lie within a common cylinder. The spacer portions 20 hold the cylindrically concave inner surfaces 18b of the segments at a greater radius than that of the outer surface 16a of the ring portion 16 and also at a greater radius than the outer surface of the ring portion of the member 14 so as to permit electrical isolation of the segments 18 from the member 14 as will presently be described in greater detail. The inner surface 16b of the ring portion 16 is also circular and of greater radius than any portion of the hexagonal cam on the timing shaft so that the member 12 may be electrically isolated from the cam 6 as will presently be described.

The member 14 is similar to the member 12 in that it is comprised of a ring portion 22 and a plurality of segments 24 each of which is connected to the ring portion 22 by spacer portions 26. The outer faces 24a of the segments 24 are also cylindrically shaped and have the same radius of curvature as the faces 18a, and all of the faces 24a lie in the same common cylinder as the faces 18a. The inner faces 24b of the segments 24 may conveniently be cylindrically concave and lie on the same radius as the inner faces 18b of the segments 18 so as to be spaced from the other ring portion 16. Similarly, the outer radius 22a of the ring portion 22 is of substantially the same radius as the outer surface 16a of the ring portion 16. However, the two members differ in that the inner surface 22b of the ring portion 22 is octagonally shaped so as to receive the cam on the timing shaft rather than being round like the ring portion 16 which must be spaced from the cam. The spacing between the segments and ring portions can best be seen in FIGS. 3 and 4 wherein it is evident that the spacer portions 26 and 20 provide the necessary separation between the segments 24 and 18, respectively, from the ring portions 16 and 22, respectively. Also, the segments 18 are circumferentially separated from the segments 24 as can best be seen in FIG. 1 so that the two members 12 and 14 are not in structural contact at any point.

The members 12 and 14 are interconnected and maintained in spaced relationship by a body of electrically non-conductive material 28 which effectively provides electrical isolation between the two members. As can be seen in FIG. 1, the body of insulating material 28 also has an octagonal inner surface 28a corresponding to the octagonal inner surface 22b of the member 14 and thereby forms an annular insulating ring portion 28b between the ring portion 16 and the cam onto which the rotary switch 10 is placed. The inner surface 28a of the resilient material 28 is also preferably provided with a plurality of very small projections 30 on each flat face of the octagonal inner surface. Each of the projections 30 may extend approximately 0.005 inch from the face, and the projections serve to accommodate the rotary switch 10 to the distributor for any one of the four major automobile manufacturers' eight-cylinder engines. Since the non-conductive material 26 will usually be a relatively resilient plastic material as will presently be described, the projections 30 can be deformed by pressing the rotary switch down over the timing shaft cam 6 and will insure that the ring portion 32 of the flat surface of the elec-

trically-conductive member 14 will always engage the timing shaft cam 6 and thereby complete the electrical circuit.

In operation, the switch member 10 is placed over the cam 6 and the brush 8 is biased against the outer periphery of the switch member formed by the several segments 12 and 14. As the switch member is rotated by the cam, the primary electrical circuit is completed through the brush to each of the conductive segments 14 and then to the cam 6, which is electrical ground. The primary circuit is opened each time that the brush leaves the conductive segments 14 and contacts the electrically-isolated segments 12 and thereby induces a pulse in the secondary circuit and fires the appropriate spark plug.

In accordance with the method of the present invention, the members 12 and 14 are formed from an electrically-conductive material in such a manner as to provide a plurality of electrically-conductive segments each having an outer cylindrical surface which may be positioned in a common cylindrical or other suitable surface, yet which can be oriented in completely spaced relationship. The preferred method of forming the members 12 and 14 is by sintering a mixture of copper and silver in the well-known and conventional manner. However, in its broader aspects the method of the present invention includes cold extruding, stamping or any other means for forming the electrically-conductive members 12 and 14, or such other members as may be desired. In general, sintering entails mixing powdered copper and silver with a suitable binder, compressing the material in a mold at a very high pressure, and then firing the material to cause the binder to fuse and form a solid metal member.

After the members 12 and 14 have been formed, the two members are placed in a mold and maintained in spaced relationship while a suitable non-conductive material, such as nylon, is injected between the two members to form the mass of material 28 which interconnects the two members and maintains the members in spaced, electrically-isolated relationship. It will readily be appreciated that the members 12 and 14 are particularly well adapted to be retained in predetermined positions within an injection mold. For example, the octagonal inner shape of the ring portion 22 of the member 14 may be slipped over an octagonal core having the necessary recesses to form the projections 30. The cylindrical portion of the mold receiving the surfaces 18a and 24a may conveniently be provided with longitudinally extending ribs to both maintain the segments 18 and 24 properly separated and also prevent the mass of non-conductive material 28 from extending outward to the cylindrical surface formed by the outer faces 18a and 24a.

From the above detailed description of a preferred embodiment of the present invention, it will be evident that a novel rotary switch construction has been described. Since all of the conductive segments are integral with an interconnecting metal ring portion, the construction has a high strength against centrifugal disintegration, and it will be noted that the bond strength between the resilient material and the metal segments is not necessarily relied upon to hold the segments in place. Due to the novel construction of the interior of the rotary switch, a single sized element will fit any of the distributors of the four major automobile manufacturers. Production of the rotary switch can be substantially automated so that the switches can be mass-produced on a very economical basis in accordance with the method of the present invention.

Although the embodiment disclosed is a novel switch for use as a circuit interrupter in an internal combustion engine ignition system, it will be appreciated from the above disclosure that more than two conductive members having conductive segments lying in the cylinder formed by the outer faces can be employed, and that the conductive segments of the various members can be deployed in substantially any circumferential order. It is also to be understood that in accordance with the broader aspects

of this invention, electrical contact with the various conductive segments can be made in any desired manner, rather than having a portion of the segments electrically connected to ground and a portion of the segments electrically insulated from ground as in the embodiment described.

The novel method for manufacturing the switch provides a means for producing the switch on a mass production basis by fully automated equipment and with great precision. In the broader aspects, the method can be used to manufacture switches having more than two sets of electrically-interconnected segments and in substantially any circumferential order.

Although a preferred embodiment of the invention has been described in detail, it is to be understood that various changes, substitutions and alterations can be made therein without departing from the spirit and scope of the invention as defined by the appended claims.

What is claimed is:

1. An improved rotary switch construction comprising: 20
a first electrically-conductive member having a plurality of segments disposed along a line on a surface of revolution,
a second member having a plurality of electrically-conductive segments disposed along the same line 25
on the same surface of revolution, and
an electrically non-conductive member interconnecting the first and second members and maintaining the first and second members in spaced relationship.
2. An improved rotary switch construction comprising: 30
a pair of integral electrically-conductive members each including a plurality of segments disposed on a surface of revolution, the segments being spaced one from the other along a line on the surface, and an integral quantity of molded electrically non-conductive material for maintaining the members in electrically-isolated relationship.
3. An improved rotary switch for disposition on a rotary shaft, the switch comprising: 40
a first electrically-conductive member consisting of a first ring portion for disposition around the shaft and a plurality of first segment portions disposed on a common radius and circumferentially spaced one from the other,
a second electrically-conductive member comprising a second ring portion for disposition around the shaft and a plurality of second segment portions disposed on the same common radius as the first segment portions and disposed between the first segment portions, 50
electrical insulating means for holding the first and second members in spaced electrically-isolated relationship, and
means for establishing electrical contact between at least one of the members and a portion of the shaft.
4. An improved rotary switch for positioning on a polygon-shaped cam of an internal combustion engine timing shaft comprising the elements set forth in claim 3 further characterized in that: 55
the inner surface of one of the ring portions is polygon-shaped to fit over the cam, and
the inner surface of the other ring portion is greater than any portion of the cam and is held in spaced relationship to the cam.
5. An improved rotary switch for positioning on a polygon-shaped cam of an internal combustion engine timing shaft comprising the elements set forth in claim 4 further characterized in that: 70
the electrical insulating means comprises a mass of somewhat resilient material and extends between said other ring portion and the cam and is adapted to engage the cam and bias the inner surface of said

one ring portion against the cam to insure electrical contact therebetween.

6. An improved rotary switch for connection to a rotary shaft, the switch comprising:

- a first electrically-conductive member comprising a first ring portion having axial, radial, and circumferential dimensions, a plurality of first segment portions connected to the first ring portion, the first segment portion being circumferentially spaced around the first ring portion and extending axially in one direction from the first ring portion, the outer surface of the first segment portion having a common radius of curvature,
- a second electrically-conductive member spaced from the first electrically-conductive member and comprising a second ring portion having axial, radial and circumferential dimensions, the second ring portion being axially spaced from the first ring portion and disposed within the extended first segment portions, a plurality of second segment portions connected to the second ring portion, the second segment portions being circumferentially spaced between the first segment portions and extending axially from the second ring portion around the first ring portion, the outer surfaces of the second segment portions having the same radius of curvature as that of the outer surfaces of the first segment portions,
- a mass of electrical insulating material disposed between and holding the members in spaced electrically-isolated relationship, and
means for making electrical contact between at least one of the members and the shaft.
7. An improved rotary switch for positioning on a polygon-shaped cam of an internal combustion engine timing shaft comprising the limitations set forth in claim 6 further characterized in that:
the inner surface of one of the ring portions is polygon-shaped to fit over the cam, and
the inner surface of the other ring portion has a radius greater than any portion of the cam and is held in spaced relationship to the cam.
8. An improved rotary switch for positioning on a polygon-shaped cam of an internal combustion engine timing shaft comprising the limitations set forth in claim 7 further characterized in that:
the mass of electrical insulating material extends between said other ring portion and the cam and is adapted to engage the cam and bias the inner surface of said one ring portion against the cam to insure electrical contact therebetween.
